UNITED STATES PATENT OFFICE.

FREDERICK A. HART, OF JERSEY CITY, NEW JERSEY, ASSIGNOR, BY MESNE ASSIGNMENTS, TO UNDERWOOD COMPUTING MACHINE COMPANY, OF NEW YORK, N. Y., A CORPORATION OF NEW YORK.

COMPUTING-MACHINE.

1,212,895.

Specification of Letters Patent. Patented Jan. 16, 1917.

Application filed June 28, 1911, Serial No. 635,762. Renewed January 21, 1913. Serial No. 743,421.

To all whom it may concern:

Be it known that I, FREDERICK A. HART, a citizen of the United States, residing in Jersey City, in the county of Hudson and State of New Jersey, have invented certain new and useful Improvements in Computing-Machines, of which the following is a specification.

This invention relates to computing machines of the class in which numeral keys are depressed to set pins or the like, and in which a general operator is afterward actuated to drive the dial wheels or other devices to various extents as determined by the keys depressed. In such machines, the general operator has been actuated manually by means of a handle: and means have been provided for insuring that the operator shall give said handle a full stroke in each direction, such means consisting of a pawl-and-ratchet mechanism, usually comprising two pawls, one being ineffective, and the other effective upon one stroke of the handle, and the converse being true upon the return stroke of the handle. The general operator has also in some cases been operated by means of an electric motor or other source of power; and in such a case the pawl-and-ratchet mechanism for insuring full stroke of the general operator, is not required or desired.

In the drawings is disclosed a machine which is provided with both a motor drive and a hand drive for the general operator, either of which can be used when desired, to the exclusion of the other; the motor gearing being shiftable out of connection with the general operator.

According to the present invention, the pawl-and-ratchet mechanism or equivalent full-stroke device is brought into use when the motor gearing is thrown out, and said full-stroke device is thrown out when the motor mechanism is brought into use.

The invention is shown in connection with a combined computing and typewriting machine of the Underwood-Hanson type, such as shown and referred to in my application No. 596,451, filed December 9, 1910. The full-stroke device comprising the invention, and applied to such machines, embodies a ratchet-wheel or segment and a pair of pawls which are alternately thrown into and out of action. I connect to the hinged frame on

which the motor-driven gearing is mounted, 55 and by which it is shifted out of use, a device for rendering both of said pawls ineffective when the motor frame is swung to bring the motor gearing into use, and for restoring to said pawls their normal functions when the motor or its gearing is thrown out. Said hinged frame with the motor-driven gearing thereon and appurtenant structure, are broadly claimed in my pending application No. 130,961, filed November 13, 1916, as a division of said application 596,451.

In the accompanying drawings, Figure 1 is a sectional side elevation of a combined typewriting and computing machine of the type aforesaid, showing the motor in use, and the full-stroke mechanism as ineffective. Fig. 2 is a sectional front elevation, showing the motor connection as dropped to a position of disuse. Fig. 3 is a perspective view of the full-stroke mechanism, showing the same in effective position. Fig. 4 is a sectional plan of the full-stroke mechanism. Fig. 5 is a sectional side elevation of the full-stroke mechanism in effective position. Fig. 6 is a part sectional front elevation of the full-stroke mechanism. Fig. 7 is a plan of the same. Fig. 8 is a side elevation, showing the full-stroke mechanism as ineffective.

The typewriting and computing mechanism includes keys having stems 1 to operate linkages 2 to set or project pins 3 upon bars 4, which are movable forwardly and carry racks 5 to mesh with pinions 6 upon dial wheels 7. The paper carriage of the typewriter operates successively links 8, connected to levers 9, for operating linkages 10, whereby the bars 4 are lifted in succession to enable their pins 3 to be set or depressed by the key linkages 2.

After the pins are set for a number, a handle 11 is grasped by the operator and pulled forward, and then returned, said handle being provided upon a crank 12. The crank is fixed upon a rock shaft 13, upon the ends of which are fixed segmental gears 14 to mesh with idle pinions 15, the latter meshing with racks 16, mounted to slide forwardly and rearwardly at the sides of the base 17 of the adding mechanism; said racks connected by a cross bar 18, which during its forward stroke engages the depressed pins 3, and drives all the racks 5

to turn all the dial wheels accordingly; another cross bar 19, (forming with the parts 13, 14, 15, 16 and 18 the general operator) being used to restore the racks at the return 5 or back stroke of the general operator.

To insure a full-stroke of the general operator in each direction, a ratchet 20 is fixed to the rock shaft 13, and gravity pawls 21, 22 are mounted to engage said ratchet, the 10 pawl 21 being effective during the forward stroke of the general operator, to prevent backward movement thereof before the forward stroke is completed; and the other pawl 22 being effective during the back 15 stroke of the general operator, to prevent forward movement thereof before said back stroke is completed.

The alternate engagement and disengagement of these pawls is effected by means of 20 tappets 23, 24, in the form of studs projecting from segment 14 or ratchet 20. At the final portion of the forward stroke of the general operator, the tappet 23 strikes a screw stop 25 fixed upon one arm 26 of a 25 three-armed lever pivoted loosely upon the rock shaft 13, and swings said lever to raise another arm 27 thereof, thereby lifting a pin or wrist 28 provided upon the pawl 21, to raise said pawl clear of the ratchet.

30 The depression of arm 26, occasioned by the engagement of the tappet 23 with the screw stop 25, permits the drop of pawl 22 into engagement with the ratchet 20, said pawl having a stud 29 which is shown at 35 Fig. 5 resting on said arm 26, to be thrown out or rendered ineffective thereby during the forward stroke of the general operator. The screw stop 25 is so set, that the pawl 21 is thrown out practically at the instant 40 of the completion of the forward stroke of the general operator.

At the completion of the return stroke of the general operator, the tappet 24 strikes a screw stop 30, thereby swinging the lever 45 26, 27 in the opposite direction, so that the pawl 21 is let into mesh, and pawl 22 is raised out of mesh, as seen at Fig. 5. Said lever has a downwardly extending arm 31 provided with notches 32, 33 in its lower 50 end, to be engaged by a spring detent 34 to hold the lever in either position; and a finger piece 35 is provided upon the lever to raise either pawl if desired.

In addition to the handle 11, there is provided a motor 37 for reciprocating the general operator when desired. The shaft 38 of this motor has a worm 39 to mesh with a gear 40 that is connected by a clutch mechanism 41 with a shaft 42, the latter having a 60 crank 43 provided at its end with a swiveled block 44, fitted to slide in an arm 45 provided upon a head 46, the latter having a neck 47 fitting in a yoke 48 secured upon one of the sliding racks 16 of the general operator. 65

By depressing a key 49, a lever 50 is vibrated to actuate a pin 51, which controls the clutch mechanism 41; and upon one complete revolution of the shaft 42, the clutch mechanism is restored to normal idle 70 position, as set forth in said application.

The gear or worm wheel 40, head 46 and intermediate parts are mounted in a frame 52, which has a hub 53 by which it is hinged loosely upon the shaft 38 of the motor, so 75 that it can be swung from the raised effective position at Fig. 1, to the dropped ineffective position at Fig. 2; a handle 54, connected to a lever 55, being provided for raising and lowering said frame 52, as explained in said application.

When the gear frame 52 is dropped, and the handle 11 is employed for reciprocating the general operator, the pawls 21 and 22 are effective in alternation, as above set 85 forth; but I provide means in connection with the gear frame 52 for throwing out said pawls whenever said gear frame is lifted from the idle position at Fig. 2 to the effective position at Fig. 1. 90

Upon the end of the gear frame is provided a projecting finger 56, which, at the elevation of said gear frame, engages a finger 57 formed upon the lower end of a vertical link or bar 58, which at its upper end is pivoted at 59 to the end of a lever 60, the latter fulcrumed at 61 upon the base 17 of the adding machine, and having lugs 62, 63 to engage and lift or hold up ears 64, 65 provided upon the pawls, thereby insuring 100 that said pawls shall both be held out of engagement with the ratchet 20. The link or bar 58 may have a shoulder 66 to rest upon one of two pins 67, by which it is guided.

When the gear frame 52 is swung down 105 to the Fig. 2 position, the members 58, 60 drop of their own weight to idle positions, thus freeing the pawls 21, 22, so that they may resume their functions.

Variations may be resorted to within the 110 scope of the invention, and portions of the improvements may be used without others.

Having thus described my invention, I claim:

1. In a machine of the character specified, 115 the combination, with a driving part; of a device for manually operating said driving part; a motor for automatically operating said driving part; a full-stroke device associated with said driving part and effective at the operation of said manual device; controlling means for alternatively connecting or disconnecting said motor with or from said driving part; and means operated automatically, consequent upon the connection 120 of the motor, for rendering said full-stroke device ineffective. 125

2. In a machine of the character specified, 130 the combination, with a driving part; of a device for manually operating said

driving part; a motor for automatically operating said driving part; a full-stroke device associated with said driving part and comprising pawl-and-ratchet mechanism, said full-stroke device effective at the operation of said manual device; controlling means for alternatively connecting or disconnecting said motor with or from said driving part; and means operated consequent upon the connection of the motor, for preventing engagement between the component members of said pawl-and-ratchet device, to render said full-stroke ineffective.

3. In a machine of the character specified, the combination, with a driving part; of a device for manually operating said driving part; a motor for automatically operating said driving part; a full-stroke device associated with said driving part, and effective at the operation of said manual device; gearing driven by said motor and adapted for connection with said driving part, to actuate the same; a frame carrying said gearing movable into and out of position to effect such connection; and means operated by said frame at its connecting movement, for rendering said full-stroke device ineffective.

4. In a machine of the character specified, the combination, with a driving part; of a device for manually operating said driving part comprising a shaft, and a handle therefor; and a full-stroke device associated with said driving part and comprising a ratchet secured to said shaft, a pair of oppositely-facing pawls capable of alternately engaging said ratchet, and a lever mounted on said shaft and provided with a pair of arms to engage and operate said pawls in alternation during the rotation of said shaft by said handle.

5. In a machine of the character specified, the combination, with a driving part; of a device for manually operating said driving part comprising a shaft, and a handle therefor; and a full-stroke device associated with said driving part and comprising a toothed, reciprocating member secured to said shaft, a pair of pawls coöperating with said member, one in each direction of movement thereof, and a controller pivoted on said shaft for operation thereby and acting to operate said pawls in alternation during the operation of said manual device.

55. 6. In a machine of the character specified, the combination, with a driving part; of a device for manually operating said driving part, comprising a shaft, and a handle therefor; and a full-stroke device associated with said driving part and comprising a ratchet secured to said shaft, a pair of oppositely-facing pawls engageable with said ratchet, and a controller mounted on said shaft for operation by the same, but having lost motion with relation thereto, said

controller provided with a pair of oppositely-projecting arms arranged to engage and operate said pawls in alternation during the rotation of said shaft by said handle.

7. In a machine of the character specified, the combination, with a driving part; of a device for manually operating said driving part, comprising a reciprocatory shaft, and a handle therefor; and a full-stroke device associated with said driving part and comprising a ratchet secured to said shaft, a pair of oppositely-facing pawls engageable with said ratchet, and a controller for operating said pawls in alternation loosely mounted on said shaft, said ratchet having a pair of projections thereon arranged to engage said controller in alternation during the opposite movements of the ratchet, to rock the same alternately in opposite directions.

8. In a machine of the character specified, the combination, with a driving part; of a device for manually operating said driving part, comprising a reciprocatory shaft, and a handle therefor; and a full-stroke device associated with said driving part and comprising a ratchet secured to said shaft, a pair of oppositely-facing pawls engageable with said ratchet, and a two-armed controller for operating said pawls in alternation loosely mounted on said shaft; each arm of the controller having a shifting member thereon, and said ratchet having a pair of projections arranged to engage said shifting members in alternation during the movements of the ratchet, to rock said controller alternately in opposite directions; said shifting members being adjustable to vary the relative timing of their engagement by said projections.

9. In a machine of the character specified, the combination, with a driving part; of a device for manually operating said driving part; a motor for automatically operating said driving part; a full-stroke device associated with said driving part, and effective at the operation of said manual device; gearing driven by said motor and adapted for connection with said driving part, to actuate the same; a carrier for said gearing movable into and out of position to effect such connection; a lever for disabling said full-stroke device; and a pendent connected to operate said lever and arranged in the path of said carrier, to be operated by the latter during its connecting movement.

10. In a machine of the character specified, the combination, with a driving part; of a device for manually operating said driving part; and a full-stroke device associated with said driving part and comprising a ratchet, a pair of oppositely-facing pawls capable of alternately engaging said ratchet, a pivotally-mounted lever pro-

vided with a pair of arms to engage and operate said pawls in alternation during the operation of said manual device, said lever having a pair of notches in one end 5 thereof, and a spring-controlled device engageable with said notches in alternation.

11. In a machine of the character specified, the combination, with a driving part; of a device for manually operating said 10 driving part; a full-stroke device associated with said driving part and comprising a ratchet, a pair of oppositely-facing pawls engageable with said ratchet, each pawl having a pair of projections thereon, and 15 a controller having a pair of arms, each

arm arranged to engage one of the projections on the adjacent pawl, so as to operate said pawls in alternation; controlling means for alternately connecting or disconnecting said motor with or from said driving part; 20 and a lever arranged to engage the other projections on said pawls consequent upon the connection of the motor, for lifting both pawls out of the sphere of action of said controller.

FREDERICK A. HART.
